UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

MIXING-MACHINE.

1,393,181.

Specification of Letters Patent. Patented Oct. 11, 1921.

Application filed June 10, 1921. Serial No. 476,457.

To all whom it may concern:

Be it known that I, THOMAS J. STURTEVANT, a citizen of the United States, residing at Wellesley, in the county of Norfolk and 5 State of Massachusetts, have invented an Improvement in Mixing-Machines, of which the following description, in connection with the accompanying drawings, is a specification, like characters on the drawings representing like parts.

The invention to be hereinafter described relates to machines for mixing materials, and is adapted more particularly for mixing the ingredients of acid phosphate or super- 15 phosphate, although it will be apparent that the machine is also useful for other purposes.

In the manufacture of acid phosphate, the ground phosphate rock and an acid, such, for example, as sulfuric acid are mixed 20 together, and may be delivered as a batch to a den or chamber where a chemical reaction takes place, resulting in the production of acid phosphate.

For economical manufacture of acid phosphate, it is desirable that the batches shall 25 be large, and in some instances they may weigh as much as one ton. It is desirable, therefore, that the mixer shall be sufficiently large to mix the large batches required. It 30 is also desirable that the mixer shall be capable of mixing one complete batch and discharge the complete batch for delivery to the den in one operation, as distinguished from incremental or installment delivery of 35 materials into the den.

One of the purposes of the present invention, therefore, is to provide a heavy, massive mixer of large capacity capable of mixing large batches of materials. In the present 40 instance of the invention, the mixer comprises a casing having paddles or elements therein for mixing the materials introduced into the casing. Simple and efficient means is provided for rotating the paddles and for 45 rotating the casing at a slow speed. The casing has a mouth or opening therein, the construction being such that the casing is slowly rotated to carry said mouth through a complete rotation. In the course of this 50 rotation, the mouth faces downward and automatically delivers the mixed materials from the slowly rotating casing. Simple and efficient means is provided automati-

cally to arrest the rotation of the casing when the mouth thereof has been brought up 55 into receiving position.

The massive rotary casing, which in some instances may weigh as much as 7000 lbs., will have considerable inertia. One of the purposes of the invention is to provide frictional means in the transmission from the driving means to the casing for gradually starting rotation of the casing and thereby preventing shear or gear teeth or other injury to the driving mechanism.

The paddles of the mixer are called upon to perform heavy duty, so that it is necessary from time to time to substitute new paddles for old ones. Another purpose of the invention, therefore, is to provide simple 70 and efficient means for detachably connecting the paddles with the rotary support therefor, and to provide a rotary casing construction having parts which may be quickly and readily separated to furnish 75 ready access to the paddles within the casing.

With the aforesaid and other purposes in view, the character of the invention will be best understood by reference to the following description of one good form thereof shown in the accompanying drawings, wherein:

Figure 1 is a plan of a mixing machine embodying the invention;

Fig. 2 is an end elevation looking toward the left of Fig. 1;

Fig. 3 is a vertical transverse section taken on line 3—3 of Fig. 1;

Fig. 4 is a detail to be referred to;

Fig. 5 is a vertical longitudinal section taken on line 5—5 of Fig. 1;

Fig. 6 is a plan view of the rotary mixer casing;

Fig. 7 is an end elevation of the casing;

Fig. 8 is a sectional detail taken on line 8—8 of Fig. 7;

Fig. 9 is a view partly in elevation and partly in section of a portion of the driving mechanism and starting and stopping mechanism; and

Fig. 10 on an enlarged scale is a vertical section taken on line 10—10 of Fig. 9.

Referring to the drawings, the machine shown therein as one good form of the invention, comprises a support for the operat-

ing mechanism of any suitable construction, and in the present instance, in the form of a base comprising longitudinal channels 1 connected by transverse channels 3.

- 5 The rotary casing 5, in the present instance of the invention, is split longitudinally into an upper part 7 (Figs. 6, 7 and 8), and a lower part 9 having outstanding end flanges 11 and 13 respectively, detachably connected by a series of bolts 15. The upper part 7 of the rotary casing is provided with a suitable mouth 17, in the present instance, of elongated form extending substantially the length of the casing. The ends of 15 the casing may be strengthened by outstanding ribs 19.

Projecting outward from the ends of the rotary casing are two-part hubs 21 and 23 having bosses 25 receiving through bolts 27 20 for detachably securing the hub parts together.

To insure registry of the upper and lower parts of the rotary casing when assembled, the hubs may have outstanding flanges 29 25 and 30. The flange 29 fits in a flanged collar 31 detachably secured to the flange 29 by bolts 33. A gear 34 has a flanged web 34^a fitting the hub flange 30 and detachably secured thereto by bolts 34^b. This flanged 30 web, therefore, and the flanged collar 31, desirably serve to insure proper registry of the upper and lower parts of the rotary casing.

When the mixer is employed to mix 35 ground phosphate rock and acid, the mixture will have a semi-liquid character, and therefore, it is desirable to prevent so far as possible, escape of liquid from the casing. Some liquid, however, may escape into the 40 hubs. Therefore, the latter may be formed to present conical recesses 35 communicating with outlet ports 37 through which the liquid may escape.

The hubs may be journaled in bearings 39 45 (Figs. 1, 2 and 5) on standards 40 rising from the base. These bearings are provided with bushings 41 fitting circumferential grooves 43 in the hubs. Oil cups 45 supply lubricant for the bearings. The bearings 50 may have caps 47 which may be detached when it is desired to separate the parts of the casing.

The means for mixing the materials in the casing, in the present instance of the invention, comprises a shaft 49 journaled in bearings 51 on standards 53 rising from the base, said bearings being provided with bushings 55 and oil cups 57.

The shaft 49 may have a portion 59 (Figs. 60 3 and 5) slabbed off so that this shaft portion, in the present instance, is of hexagonal form.

Projecting through elongated transverse holes 61 in this shaft portion, are mixing 65 elements, in the present instance, in the form

of paddles 63 having straight shanks and heads 65. The shank of each paddle may be of a width substantially corresponding to the longer dimension of the elongated opening 61 therefor. The shank may have a lateral recess 67 (Fig. 4) of a length corresponding to the length of the hole 61. A tapered gib 69 is adapted to be driven into the hole to secure the paddle therein. To mount the paddle on the shaft, its shank is 70 inserted through the hole 61 until the lateral recess 67 is in registry with said hole. Thereupon, the paddle may be shifted laterally, and the gib 69 may be driven in the hole and secure the paddle to the shaft. When it is 75 desired to remove the paddle from the shaft, the gib is knocked out, and the paddle is shifted laterally and withdrawn from the hole. Thus, the paddles may be quickly and 80 easily assembled with the shaft, and removed 85 therefrom as desired.

The shaft may have flanges 71 (Fig. 5) thereon adapted to seat in recesses 72 in the ends of the casing, and the shaft may have flanges 73 occupying the conical recesses 35 90 in the hubs, and adapted to deflect any liquid escaping past the flanges 71 toward the ports 37 referred to. To prevent escape of liquid outward toward the ends of the hubs, sleeves 75 may be seated in recesses in the hubs, and have inturned flanges 71 for engagement 95 with portions of the shaft 49.

It will be noted that the casing hubs rotate in bearings which support the heavy 100 casing independently of the shaft, and as a consequence, the shaft is relieved of the weight of the casing.

A suitable housing may be provided for the rotary casing. In the present instance, a housing 79 (Figs. 1, 2, 3 and 5) is provided split to present a lower portion 81 mounted on and secured to the base, and an upper portion 83 resting on the lower portion. These portions have outstanding flanges 85 detachably secured together by 105 bolts 87.

In the top of the upper housing portion 83 is a neck 89 adapted to deliver materials from a hopper 91 (Fig. 5) to the mouth 17 of the rotary casing when the mouth is in 115 registry with said neck. Acid or other liquid may be delivered to the mouth of the mixer through a pipe 93 which may have an end entered either in a hole 95 or a hole 97 in the top of the upper portion of the housing. If 120 one of these holes is not used, it may be closed by a cap 99.

To enable ready access into the interior of the housing to free the same from any materials which may collect thereon, the upper 125 housing portion 83 may be provided with inclined ends 101 having openings 103 therein normally closed by covers 105 provided with handles 107.

Suitable means may be provided to rotate 130

the paddle shaft 49. This means, in the present instance, comprises a shaft 109 (Figs. 1, 2 and 5) journaled in bearings 111 on standards 113 rising from the base. This 5 shaft is provided with a tight pulley 115 and a loose pulley 117 adapted to receive a belt which may be driven from any suitable source of power.

Fast on the shaft 109 is a pinion 119 meshing with a large gear 121 fast on the paddle shaft 49.

Suitable means may be provided for slowly rotating the mixer casing 5. In the present instance, this is accomplished by a 15 transmission driven from the paddle shaft 49. This transmission may comprise a stub shaft 123 (Figs. 1, 5, 9 and 10) having a disk plate 125 projecting from one end thereof secured by bolts 127 to a flange 129 on 20 one end of the paddle shaft 49.

A pinion 131 is mounted loose on the stub shaft 123, and meshes with a large gear 133 on a back shaft 135 journaled in bearings 137 on standards 139 rising from the base. 25 Fast on the back shaft is a pinion 141 meshing with the gear 34 referred to, which is secured to one of the hubs of the rotary casing.

The pinion 131 has clutch teeth 143 projecting laterally from one end thereof for coöperation with clutch teeth 145 projecting from a friction disk 147 loose on the stub shaft 123. This friction disk has a series of 30 holes 149 adjacent the periphery thereof 35 adapted to receive inserts 151 of wood or other suitable material.

Opposed to these inserts is a ring 153 yieldingly urged toward the disk plate 125 by coil springs 155 having ends encircling 40 studs 157 projecting from the disk plate. These coil springs may be confined between said disk plate and caps 159 on bolts 161 entered through the ring 153 and disk plate.

The construction is such that the inserts 45 151 will be pressed by the coil springs into frictional engagement with the ring 153, and the disk plate 125, and when the pinion 131 is slid on the stub shaft 123 to bring its teeth 143 into clutching engagement with 50 the friction plate teeth 145, the drive will be frictionally transmitted from the paddle shaft 49 to the pinion 131. The drive will be transmitted from the latter through the gear 133, pinion 141 and gear 34 to the rotary casing 5. The frictional connection between the paddle shaft 49 and stub shaft 123 55 will enable the ring 153 and disk plate 155 to slip relatively to the inserts of the friction plate, so as gradually to overcome the inertia of the massive casing and start the 60 rotation thereof without liability of shearing gear teeth of the transmission, or other injury thereto.

Suitable means may be provided for sliding 65 the pinion 131 along the stub shaft to

connect the clutch, and suitable means may be provided automatically to disconnect the clutch to arrest rotation of the mixer casing when the mouth of the latter comes into registration with the hopper neck 89.

70

To accomplish this, in the present instance, a pair of arms 163 (Figs. 1, 5 and 9) may be mounted fast on a rock shaft 165 carried by brackets 167 projecting laterally from the base, and the upper ends of said arms may have pins 169 entered into a circumferential groove 171 in the hub of the pinion 131.

Fast on the rock shaft 165 is an arm 173. Pivotedly connected to the free end of the 80 arm 173 is a stop arm 175 having a nose 177 adapted for engagement with a stop lug 179 projecting from the face of the gear 34 referred to.

To move the stop arm 175 into and out of 85 position for engagement with the stop lug 179, and to hold the stop arm in position for engagement with the stop lug, a toggle device 181 may be provided comprising links 183 and 185 connected by a pin 187. The link 183 is pivotally connected by a pin 189 with the stop arm, and the link 185 is mounted fast on a rock shaft 191 mounted in brackets 193 on one of the paddle shaft 90 bearings 51. The toggle link 183 has an extension 195 projecting over the link 185, and said extension is provided with a stop screw 197. A handle 199 fast on the rock shaft 191, enables manual operation of the toggle, and this handle may be provided 100 with suitable connections enabling distant control of the toggle if desired.

Pivotedly connected to and depending 105 from the arm 173 referred to, is a rod 201 projecting through a plate 203 on the base. A coil spring 205 encircles the rod, and is confined between the plate 203 and a cup 207 seated on a head 209 on the rod and limited by a nut 211. A larger and heavier coil spring 213 encircles the coil spring 205 110 and rests on the head 209, said spring 213 being shorter than the spring 205.

When it is desired to close the clutch to 115 initiate rotation of the casing, the handle 199 is rocked in a contraclockwise direction, thereby buckling the toggle and withdrawing the stop arm 175 out from engagement with the stop lug 179 on the gear 34. Thereupon, the coil spring 205 operates through the rod 201 to pull the arm 173 downward, which rocks the arms 163 toward the right, thereby sliding the pinion 131 along the stub shaft 123, and causing the pinion clutch teeth 143 to engage the friction plate clutch teeth 145.

Then the drive will be transmitted from the shaft 49 through the frictional device, and the clutch teeth to the pinion 131, which will rotate the gear 133, pinion 141, and gear 34, and cause the casing to rotate.

130

The casing having received a batch of materials to be mixed, will slowly rotate to carry its mouth 117 through a complete rotation. As the mouth approaches its lowest position, it discharges the mixed materials from the casing, and the motion of the latter is sufficiently slow to readily permit this discharge.

The stop lug 179 is so positioned on the 10 gear 34, that when said stop lug has been rotated around into contact with the stop arm nose 177, the mouth of the casing will be in registry with the hopper neck 89.

When the stop lug 179 engages the stop 15 arm nose 177, the gear 34 pulls the stop arm 175 upward, thereby rocking the arm 173 upward, which throws the arms 163 to the left, thereby opening the clutch. As the arm 173 rocks upward, the coil spring 213 20 is brought into engagement with the plate 203, and said spring serves yieldingly to arrest the rotation of the casing. Thus, the momentum of the massive casing is gradually overcome, and the casing is brought to 25 rest without injury to the mechanism.

When the toggle is straightened, it securely holds the stop arm in position to be engaged by the stop lug 179. Since the nose of the stop arm is offset to the right from 30 the axis of the pin connecting the stop arm with the arm 173, on engagement of the lug with the nose, there is a component of force tending to rock the stop arm in a counter-clockwise direction. To prevent liability of 35 buckling of the toggle from this force, the stop screw 197 may be adjusted so that when the toggle is in locking position, the axis of the pin 197 connecting the toggle links will be somewhat beneath a straight line passing 40 through the axes of the pins 189 and 191. The consequence is, that the component of force referred to, will tend to buckle the links downward, but this will be resisted by the engagement of the stop screw 197 45 with the upper edge of the toggle link 185.

By the mixing machine described, batches of materials to be mixed may be introduced into the rotary casing, and they will be thoroughly mixed by the paddles therein which 50 may be continuously rotated. The character of the transmission from the paddle shaft to the rotary casing may be such that a proper speed reduction is obtained, so that by the time the rotary casing is turned 55 through an arc of substantially 180° , or one-half rotation, sufficient time will have elapsed to enable the batch in the casing to be mixed properly. Thus, the transmission in a sense is a timing mechanism which will 60 automatically determine the minimum mixing period, and this construction insures that successive batches will be mixed at least the minimum length of time.

When the mixer casing has been rotated to 65 move its mouth past discharge position, the

materials will be automatically discharged, and when said mouth has been brought back to receiving position, the rotary casing will be automatically arrested without attention on the part of the operator. After the next 70 batch has been delivered into the rotary casing, the operator shifts the handle 199 to close the clutch and initiate rotation of the casing, and the operations are repeated as described in respect to the previous batch. 75

The stopping mechanism described serves automatically to bring the rotary casing to rest with the mouth of the casing in position to receive materials from the delivery opening 89 of the housing, but since the casing 80 9 rotates at a relatively slow speed, it may be desirable, in some cases to introduce the batch of materials into the casing without stopping the casing. To this end, the mouth 17 of the casing is made considerably wider 85 than the delivery opening or neck 89 as will be apparent from Fig. 3, so that the mouth, although moving, will remain opposite the delivery opening 89 long enough to receive 90 the charge of materials.

To operate the mixing machine with the casing 9 rotating continuously, it is simply necessary to retain the stop arm 175 out of its operative position, and this may be done by holding or securing the handle 199 in its 95 trip position. By both charging and discharging the casing 9 during the rotation thereof, the length of time each batch of material remains in the casing is controlled accurately, and as a result each batch will 100 be mixed in the same length of time.

When it is desired to have access to the paddles in the rotary casing, the bolts connecting the upper housing portion with the lower housing portion are removed, and the upper housing portion is lifted from the lower housing portion. When the flanged collar 31 and gear 34 are detached from the hubs 21 and 23, the bolts connecting the upper part of the rotary casing with the 110 lower part are removed, the caps of the bearings for the hubs of the rotary casing are lifted, and then the upper part of the rotary casing may be removed, thereby exposing 115 the paddles and their supporting shaft. If it is desired to substitute a new paddle for an old one, this may be readily accomplished by knocking out the lock gib therefor, and the old paddle may be removed from the shaft and a new one substituted therefor as 120 described.

The mixer described is strong and simple in construction, reliable in operation, and not likely to get out of order.

It will be understood that the invention 125 is not limited to the specific embodiment shown, and that various deviations may be made therefrom without departing from the spirit and scope of the appended claims.

What is claimed is:

1. A machine for mixing materials, comprising, in combination, a rotary casing having a mouth disposed between the ends of the casing for receiving and discharging materials, hubs projecting from opposed ends of said casing, bearings supporting said hubs, a shaft projecting through said rotary casing and hubs, bearings for said shaft, mixing elements carried by said shaft, means to rotate said shaft, and a speed reduction transmission for rotating said casing from said shaft.
2. A machine for mixing materials, comprising, in combination, a rotary casing having a mouth formed in a wall of the casing for both receiving and discharging materials, bearings supporting said casing, a shaft projecting through said casing having mixing elements thereon, bearings for said shaft to support the same independently of said casing, and driving means for said casing and shaft having provision for rotating the former at a slower speed than the latter.
3. A machine for mixing materials, comprising, in combination, a rotary casing, hubs projecting from opposed ends of the casing, bearings supporting the hubs, a shaft extending through the hubs and casing and having elements thereon for mixing materials within the casing, means independent of the casing for supporting the shaft, means acting through one of said hubs to rotate the casing, and means for rotating the shaft at a speed different from the speed of the drum.
4. A machine for mixing materials, comprising, in combination, a rotary casing, a shaft projecting through said casing having mixing elements thereon, means to drive said shaft, a back shaft, gears for rotating the back shaft from the mixer shaft, and gears, one of which operates through an end of the casing to rotate the casing from the back shaft.
5. A machine for mixing materials, comprising, in combination, a rotary casing having a mouth disposed between the ends of the casing for receiving and discharging materials, a shaft projecting through said casing having mixing elements thereon, bearings for said casing, bearings for said shaft, a back shaft, a gear on said casing, a pinion on the back shaft meshing with said gear, a gear on the back shaft, and a pinion driven by the mixer shaft and rotating the back shaft gear.
6. A machine for mixing materials, comprising, in combination, a rotary casing, a shaft projecting therethrough having mixing elements thereon, bearings for said casing, bearings for said shaft, speed reduction gears at one end of the shaft for driving said shaft, and speed reduction gears driven from the opposite end of said shaft for rotating said casing.
7. A machine for mixing materials, comprising, in combination, a rotary casing having a mouth disposed between the ends of the casing for receiving materials when the mouth is in the upper position, and for discharging materials when the mouth is in the lower position, a shaft projecting through the casing and having mixing elements thereon for mixing materials introduced into said casing, means to rotate said shaft, and speed reduction means to impart rotation from said shaft to said casing at a speed sufficiently slower than the shaft to effect mixing of the materials while the casing mouth is moved from the upper to the lower position.
8. A machine for mixing materials, comprising, in combination, a base, two sets of bearings mounted thereon, a rotary casing having oppositely projecting hubs journaled in one of said sets of bearings, a shaft journaled in the other set of bearings and having mixing elements thereon, and means to transmit rotation from said shaft to said casing.
9. A machine for mixing materials, comprising, in combination, a rotary casing, a shaft having mixing elements thereon within the casing, means to rotate said shaft, a transmission for imparting rotation from said shaft to said casing including frictional means gradually to initiate rotation of said casing, and clutch means controlling the driving connection between said shaft and casing.
10. A machine for mixing materials, comprising, in combination, a rotary casing having a mouth for receiving and discharging materials, means within the casing for mixing the materials therein, means slowly to rotate said casing, and means automatically to arrest rotation of said casing when said mouth is in position to receive materials.
11. A machine for mixing materials, comprising, in combination, a rotary casing having a mouth for receiving and discharging materials, means within the casing for mixing the materials therein, means slowly to rotate said casing to move its mouth from receiving to discharging position, and means automatically to arrest rotation of said casing when its mouth has been moved back to receiving position.
12. A machine for mixing materials, comprising, in combination, a rotary casing having a mouth for receiving and discharging materials, means for mixing the materials introduced into said casing, and means slowly to rotate said casing to move its mouth from receiving to discharging position, thereby to determine automatically the minimum duration of the mixing operation.
13. A machine for mixing materials, comprising, in combination, a rotary casing, a shaft projecting therethrough having mixing elements thereon, said casing having a mouth

- for receiving and discharging materials, speed reduction means for rotating the casing from said shaft at a slower speed than the latter to move the casing mouth from 5 receiving to discharging position, and means automatically to arrest rotation of the casing after said mouth has been moved to discharging position.
14. A machine for mixing materials, comprising, in combination, a rotary casing having a mouth for receiving and discharging materials, a shaft having mixing elements thereon, a gear for rotating said casing, and means operated by said gear for automatically 10 arresting rotation of said casing each time it makes a complete rotation.
15. A machine for mixing materials, comprising, in combination, a casing, means for mixing materials introduced into said casing, a shaft for said mixing means, and a transmission between said shaft and casing including a clutch and frictional driving means.
16. A machine for mixing materials, comprising, in combination, a casing, a shaft having mixing elements thereon for mixing materials introduced into said casing, and a transmission between said shaft means for 25 rotating said shaft casing for rotating the latter from the former and including a clutch, and means automatically to open said clutch to arrest rotation of said casing.
17. A machine for mixing materials, comprising, in combination, a rotary casing, a shaft having mixing elements thereon for mixing materials introduced into said casing, a transmission between said shaft and casing including a clutch, and means controlled by said transmission automatically 30 to open said clutch to arrest rotation of said casing.
18. A machine for mixing materials, comprising, in combination, a rotary casing, a shaft having elements thereon for mixing materials, a transmission between said shaft and casing for rotating the latter from the former, said transmission having a clutch, manually operable means to close said clutch to initiate rotation of said casing, and means 45 automatically to arrest the rotation of said casing after it has turned a predetermined extent.
19. A machine for mixing materials, comprising, in combination, a rotary casing, a shaft having elements thereon for mixing materials introduced into said casing, transmission gears between said shaft and casing, a clutch coöperating with said transmission gears, a lug on one of said gears, a stop arm, 50 means to move said stop arm into and out of the path of said lug, and means connecting said stop arm with said clutch, that the lug on the gear on engagement with said stop arm, may open said clutch and arrest rotation of said casing.
20. A machine for mixing materials, comprising, in combination, a rotary casing, a shaft having elements thereon for mixing materials introduced into said casing, a gear transmission between said shaft and casing 70 including a clutch, and means operated by one of the gears of said transmission for automatically opening said clutch to arrest rotation of said casing.
21. A machine for mixing materials, comprising, in combination, a rotary casing, a shaft having mixing elements thereon for mixing materials introduced into said casing, a transmission between said shaft and casing including a clutch, means automatically 80 to open said clutch to arrest rotation of said casing, and means gradually to check the momentum of the casing in bringing the latter to rest.
22. A machine for mixing materials, comprising, in combination, a rotary casing having a mouth for receiving and discharging materials, a shaft having elements thereon for mixing materials introduced through 85 said mouth into said casing, a transmission between said shaft and casing, and means automatically to interrupt said transmission to arrest rotation of said casing when said mouth is brought to receiving position.
23. A machine for mixing materials, comprising, in combination, a rotary casing having a mouth for receiving and discharging materials, a shaft having elements thereon for mixing materials introduced through 90 said mouth into said casing, a transmission between said shaft and casing, and means automatically to interrupt said transmission to arrest rotation of said casing when said mouth is brought to receiving position, said arresting means including yieldable means 95 to check the momentum of the casing and bring it to rest.
24. A machine for mixing materials, comprising, in combination, a rotary casing, a shaft having elements thereon for mixing 100 materials introduced into said casing, a gear transmission between said shaft and casing including a clutch, a stop element on one of the gears of said transmission, a stop member movable into and out of the path of said 105 stop element, and means operated by said member to open said clutch when said stop element is rotated into engagement with said stop member.
25. A machine for mixing materials, comprising, in combination, a rotary casing, a shaft having elements thereon for mixing materials introduced into said casing, a gear transmission between said shaft and casing including a clutch, a stop element on one of 110 the gears of said transmission, a stop member movable into and out of the path of said stop element, means operated by said member to open the clutch automatically on 115 movement of said member by engagement of 120 said member by engagement of 125 130

said element therewith, and toggle means for holding said member in the path of said element.

26. A machine for mixing materials, comprising, in combination, a rotary casing, a shaft having elements thereon for mixing materials introduced into said casing, a gear transmission between said shaft and casing including a clutch, a stop element on one of the gears of said transmission, a stop member movable into and out of the path of said stop element, means operated by said member to open the clutch automatically on movement of said member by engagement of said element therewith, and toggle means for holding said member in the path of said element.

27. A machine for mixing materials, comprising, in combination, a rotary casing, a shaft having elements thereon for mixing materials introduced into said casing, a gear transmission between said shaft and casing including a clutch, a stop element on one of the gears of said transmission, a stop member movable into and out of the path of said stop element, means operated by said member to open the clutch automatically on movement of said member by engagement of said element therewith, toggle means for holding said member in the path of said element, means to buckle said toggle to move said member out of the path of said element, and means released thereby automatically operating to close said clutch.

35. 28. A machine for mixing materials, comprising, in combination, a rotary casing, a shaft having elements thereon for mixing materials introduced into said casing, a gear transmission between said shaft and casing including a clutch, a rock arm for shifting said clutch, a member for rocking said arm, a spring coöperating with said member to close the clutch, a stop arm connected to said member, and a stop element on one of the gears of said transmission for engagement wth said stop arm to rock said member against the resistance of said spring to open said clutch and arrest rotation of said casing.

29. A machine for mixing materials, comprising, in combination, a rotary casing for receiving and discharging materials, means for mixing the materials in said casing, means frictionally to initiate rotation of said casing, and means to arrest rotation of said casing including means yieldingly to check the momentum of said casing in bringing it to rest.

30. A machine for mixing materials, comprising, in combination, a rotary casing for receiving and discharging materials, means to mix materials in said casing, means for rotating said casing including a frictional clutch for gradually initiating rotation of said casing, and means to arrest rotation of said casing including a spring for gradually

absorbing the momentum of said casing in bringing the same to rest.

31. A machine for mixing materials, comprising, in combination, a rotary casing for receiving and discharging materials, means for mixing materials introduced into said casing, means for rotating said casing including means frictionally to initiate its rotation, means automatically to arrest rotation of said casing, and means yieldingly to check momentum of the casing as it comes to rest.

32. A machine for mixing materials, comprising, in combination, a rotary casing having a mouth for receiving and discharging materials, means for mixing materials introduced into said casing, driving means to rotate said casing including means gradually to overcome the inertia of the casing and initiate its rotation, means controlled by the rotation of said casing automatically to arrest its rotation, and means to absorb the momentum of said casing in coming to rest.

33. A machine for mixing materials, comprising, in combination, a casing for receiving and discharging materials, means for mixing materials introduced into said casing, driving means for rotating said casing including a positive clutch and a frictional device, and means automatically to open the clutch to interrupt the drive for said casing and stop the casing in a predetermined position.

34. A machine for mixing materials, comprising, in combination, a casing for receiving and discharging materials, means for mixing materials introduced into said casing, driving means for rotating said casing including a positive clutch and a frictional device, means automatically to open the clutch to interrupt the drive for said casing, and means to arrest the casing after opening of said clutch.

35. A machine for mixing materials, comprising, in combination, a rotary casing constructed of longitudinally separable sections removably secured together and having a mouth disposed between the ends of the casing for receiving and discharging materials, a shaft projecting through said casing having mixing elements thereon, and means detachably to secure said elements to said shaft, said means being accessible on separation of said sections.

36. A machine for mixing materials, comprising, in combination, a rotary casing constructed of longitudinally separable sections and having a mouth disposed between the ends of the casing for receiving and discharging materials, means detachably to connect said sections, a shaft having holes therein, paddles projecting through said holes, and gibs detachably to secure said paddles in said holes.

37. A machine for mixing materials, com-

prising, in combination, a rotary casing, a shaft having holes therein, paddles having shanks insertible in said holes, each shank having a notch arranged to engage the shaft 5 and determine the adjustment of the shank within a hole of the shaft, and gibs adapted to wedge between said shanks and walls of said holes to secure the paddles to the shaft.

38. A machine for mixing materials, comprising, in combination, a rotary casing, a shaft having holes therein, paddles having shanks insertible through said holes, each shank having a shoulder adapted to engage the shaft and determine the adjustment of the shank through a hole of the shaft, and gibs insertible in said holes between said shanks and walls of the holes to secure the paddles to the shaft.

39. A machine for mixing materials, comprising, in combination, a rotary casing formed of separable, substantially semi-cylindrical sections, means to insure registry of said sections, means detachably to connect said sections, means for mixing materials introduced into said casing, and means for rotating said casing and mixing means.

40. A machine for mixing materials, comprising, in combination, a rotary casing having hubs projecting from opposite ends thereof, bearings for said hubs, said casing and hubs being split longitudinally to form two parts, means detachably to secure said parts together, and means for mixing materials introduced into said casing.

35 41. A machine for mixing materials, comprising, in combination, a rotary casing formed of parts detachably secured together and having an opening adapted to both receive and discharge materials, means for mixing materials introduced into said casing, means for slowly rotating said casing from receiving to discharging position, and a housing inclosing said rotary casing having separable parts to allow access to said casing.

42. A machine for mixing materials, comprising, in combination, a rotary casing having parts separable sections detachably connected, a shaft projecting through said rotary casing having mixing elements thereon, means detachably to connect the mixing elements with said shaft, means for rotating said shaft and casing at different speeds, and a housing having parts separable to permit separation of the rotary casing sections and allow access to the means for detachably connecting the mixing elements with said shaft.

43. A machine for mixing materials, comprising, in combination, a rotary casing for receiving and discharging materials, means for mixing the materials in said casing, a sectional housing for said rotary casing spaced therefrom and having an opening in one of the sections and a cover for said

opening adapted to be removed to allow access to the space between said casing and housing.

44. A machine for mixing materials, comprising, in combination, a rotary mixing casing having axially separable sections removably secured together, a shaft extending axially through said casing and having mixing elements thereon for mixing materials introduced into the casing, means to rotate the casing and shaft, and means including co-operating annular flanges on the shaft and wall of the casing to resist escape of materials from said casing along the shaft, the shaft with the flange thereon being movable to and from operable position upon separation of said sections.

45. A machine for mixing materials, comprising, in combination, a rotary mixing casing having axially separable sections removably secured together, a shaft extending axially through said casing and having mixing elements thereon for mixing materials introduced into the casing, means to rotate the casing and shaft, and means upon the shaft and end walls of the casing to resist escape of materials from the casing along the shaft, including flanges projecting into co-operating recesses, the co-operating flanges and recesses being separable upon separation of said sections and removal of the shaft.

46. A machine for mixing materials, comprising, in combination, a rotary mixing casing formed of longitudinally separable sections, a shaft within said casing having elements for mixing materials therein, means for securing said sections in registry including annular flanges on the sections and collars tightly embracing the flanges, and means for rotating the mixing casing.

47. A machine for mixing materials, comprising, in combination, a rotary mixing casing formed of longitudinally separable sections having hubs at the opposite ends of the casing, bearings supporting said hubs, means for rotating the casing, means for mixing the materials within the casing, and means for securing said sections in registry including annular surfaces on said hubs and collars tightly embracing said surfaces.

48. A machine for mixing materials, comprising, in combination, a rotary mixing casing having hubs at the ends thereof, a mixing shaft extending through the casing and hubs and having elements thereon for mixing materials introduced into said casing, means to rotate said casing, and means for preventing materials from working along said shaft, including a pocket formed within each hub to surround said shaft and having drain conduits radiating from the pocket outwardly through the walls of the hub, and flanges upon the shaft within said pockets to cause the materials working along the shaft to drop into the pockets.

49. A machine for mixing batches of materials, comprising, in combination, a rotary casing having a mouth disposed between the ends of the casing for receiving materials 5 when the mouth is in the upper position and for discharging materials when the mouth is in the lower position, means for rotating the casing continuously, means for introducing a batch of materials through the mouth of the 10 casing during the rotation thereof, and means for mixing the batch of materials while the casing rotates from the receiving to the discharge position.
50. A machine for mixing batches of materials, comprising, in combination, a rotary 15
- casing having a mouth through which the batch of materials enters and leaves the casing, means for rotating the casing continuously, means for introducing a batch of materials into the casing during the rotation 20 thereof, a mixing shaft extending through said casing and provided with mixing elements, and means for operating said shaft to complete the mixing operation while the casing rotates from the receiving to the 25 discharge position.

In testimony whereof, I have signed my name to this specification.

THOMAS J. STURTEVANT.
